227,932

COMBINED LABEL PRINTER AND APPLICATOR

Robert P. Mulholland, Centerville, Paul H. Hamisch, Jr., Franklin, and William A. Jenkins, Englewood, Ohio, assignors to Monarch Marking Systems, Inc., Dayton, Ohio

Filed Jan. 26, 1972, Ser. No. 221,131

Term of patent 14 years

Int. Cl. D18—02

U.S. Cl. D64—10

FIG. 1 is a side perspective view of a combined label printer and applicator showing our new design;

FIG. 2 is an elevational view of the opposite side thereof;

FIG. 3 is an elevational view of the side shown in FIG. 1;

FIG. 4 is a rear elevational view looking towards the left of FIG. 3;

FIG. 5 is a front elevational view looking towards the right of FIG. 3;

FIG. 6 is a top plan view of FIG. 2; and

FIG. 7 is a bottom plan view thereof.

We claim:

The ornamental design for a combined label printer and applicator, substantially as shown.
